SIGNAL DEVICE

Lloyd Rittenhouse, Honeoye Falls, N. Y., assignor
to The A. E. Rittenhouse Co., Inc., Honeoye
Falls, N. Y., a corporation of New York

Application June 5, 1939, Serial No. 277,474

5 Claims. (Cl. 177—7)

This invention relates to improvements in signal devices, with particular reference to the type of construction including a housing with a chime bar or element secured exteriorly of the housing and an electrically operated striker mechanism such as a solenoid arranged within the housing, and it has for its object to afford a compact construction that is of neat and ornamental appearance, efficient in operation, and can be manufactured and assembled at a low cost.

A further purpose of the invention is to provide a structure embodying a housing including front and back walls which are held in operative relation by any suitable means permitting ready assembly, and in which the front and back walls maintain or clamp the solenoid in operative position without the need of additional attaching means, the solenoid being independent of both the front and back walls and held in operative position by said walls when they are assembled.

A further object of the invention is to afford a construction in which a proper signal or tone can be had by locating an opening in the front wall at one end of the housing opposite the adjacent end of the chime bar or element, while locating the solenoid or striker-operating means centrally of the chamber with its plunger tube located in and extending through a central opening in the front wall of the housing.

An additional purpose of the invention is to afford a construction of housing and separable back wall that permits of readily assembling the parts and easily installing a unit in operative position on a wall or suitable support, with the operating mechanism all spaced from the wall and completely housed and protected.

To these and other ends, the invention consists in the construction and arrangement of parts that will appear from the following description when read in conjunction with the accompanying drawing, the novel features being pointed out in the claims following the specification.

In the drawing:

Fig. 1 is a view in front elevation of a signal device incorporating one embodiment of the invention;

Fig. 2 is a vertical sectional view of the same on line 2—2 of Fig. 1;

Fig. 3 is a side elevation of the removable back plate showing the position of the solenoid and plunger tube as it is about to be assembled and positioned in the housing in operative relation to the front and back walls thereof;

Fig. 4 is a detailed sectional view through the plunger tube of the solenoid;

Fig. 5 is an end elevation of the structure shown in Fig. 1, and

Fig. 6 is a side elevation of the back wall, partially broken away, and showing the position of the solenoid thereon.

Referring more particularly to the drawing in which like reference characters refer to the same parts throughout the several views, the structure shown, which is exemplary of one embodiment of the invention, includes a housing comprising a 10 curved front wall 1 and flat end walls 2 and 3, the end wall 2 being closed and the end wall 3 having one or more sound-emitting openings 4 therein.

Secured to the front wall 1 is a chime element 15 or bar 5 mounted as usual in this class of devices, and 6 is an opening at one end of the front wall opposite the adjacent end of the chime bar 5, the space 7 within the housing thus serving as a resonance chamber when the chime bar is struck 20 to give a musical note or signal. The end 2 of the housing includes an upwardly extending lug 8 by which the unit can be secured to a wall or other suitable support.

The front wall 1 has a central inwardly embossed flat portion 9 having an opening arranged centrally thereof, while 10 designates the removable back wall which also preferably has a central embossed portion 11 having a central opening 30 being adapted to receive the tube 12 fixedly arranged within the solenoid coil 13 which constitutes the electrical striker operating means.

Arranged for movement within the tube 12 is a solenoid plunger 14 carrying the striker tip 15 35 that is movable outwardly to engage the chime bar 5 when the solenoid is energized. 16 is a spring held within the outer end of the tube 12 and acting to move the striker out of engagement with the chime bar after the signal is given, while 40 17 is a plug of felt or other suitable material held within the inner end of the tube 12 by means of a removable spring cap 18 for keeping the plunger within the tube 12. The solenoid 13 includes 45 disks 19 at the ends of the coil surrounding the tube 12, which latter is adapted to fit closely within the central openings in the back and front walls 1 and 10 while the disks 19 abut the central embossed portions 9 and 11.

The solenoid is separable from the front and back walls and is held in operative position by being clamped therebetween. The back wall 10 includes outwardly extending flanges 20 at its outer edge, said flanges being adapted to engage the spring locking lugs 21 which are struck in- 55

wardly from the end walls 2 and 3. The position of the lugs 21 with relation to the flanges 20 is such that the back wall when pushed inwardly will just clear the lugs 21 and be retained thereby 5 when the back wall is moved in far enough to force the solenoid tightly against the front wall of the housing and hold it in such position.

The solenoid 13 is assembled in relation to the back wall with the inner end of the tube 12 extending through the central opening in the back wall, and the coil being grounded to the back wall preferably as at 22, while 23 and 24 designate the usual binding posts or connections for the conductors, connection 24 being associated 15 with the conductor 25 leading to the solenoid coil.

With the parts in the position shown in Fig. 3, the solenoid being loosely arranged on the back wall, the back wall and solenoid are inserted into the housing from the rear thereof and the solenoid manipulated until the front end of the tube 12 enters the central opening in the front wall 1, as shown in Fig. 2. Then the back wall is forced inwardly as far as it will go over the spring lugs 21 until the latter engage the flanges 20 and hold 25 the back wall in operative position with the solenoid fixedly retained between the front and back walls.

With the parts in this assembled relation, when the solenoid circuit is closed, the striker moves 30 outwardly through the tube 12 located in the central opening of the front wall 1 and engages the chime bar 5, and the vibrations therein set up are transmitted through the opening 6 into the resonance chamber 7, the sound being emitted through the opening 8 and openings 4.

It will be observed that the end walls 2 and 3 are of sufficient width so that when the back wall is inserted and occupies its locked position, the inner end of the tube 12 and the spring cap 18 40 do not extend beyond the rear edges of the housing. Thus the latter can be positioned against a wall or support without having to provide an opening therein to accommodate the solenoid tube.

45 This construction avoids the necessity of permanently attaching the solenoid by brackets or otherwise to a part of the housing and affords a construction in which the parts can be manufactured at a minimum cost and readily assembled, resulting in an extremely low priced, efficient, and ornate chime signal.

While the invention has been described with relation to the particular construction and arrangement herein disclosed, it is not confined to the details set forth, and this application is intended to cover any modifications or changes 55

coming within the purposes of the invention or the scope of the following claims.

I claim:

1. In a signal device, the combination with a housing including front and back walls having opposite openings therein, of a solenoid held between said front and back walls and including a plunger tube extending through said openings, a chime element secured to the front wall, said front wall having a sound opening opposite a portion of the chime element, and means acting to hold the back wall in operative position and thereby clamp the solenoid against the front wall. 5

2. In a signal device, the combination with a housing including front and back walls and end walls, the front wall having a central opening therein, a solenoid located within said housing in contact with the front and back walls and having a plunger tube extending through and fitting 20 closely in said opening, and a chime element secured to the front wall, said front wall having a sound opening opposite a portion of the chime element and the opposite end wall having an opening therein. 25

3. In a signal device, the combination with a housing including front and back walls, the front wall having a central opening therein, a solenoid located within said housing in contact with the front and back walls and having a plunger tube 30 extending through and fitting closely in said opening, and a chime element secured to the front wall, said front wall having a sound opening opposite a portion of the chime element.

4. In a signal device, the combination with a housing including separable front and back walls having oppositely disposed central openings therein, of a solenoid held between said front and back walls and having a plunger tube extending through said openings, a chime element 40 secured to the front wall, said front wall having a sound opening opposite a portion of the chime element, and retaining means engageable with said separable back wall acting to hold it in operative position against the solenoid and in spaced relation to the rear edge of the housing. 45

5. In a signal device, the combination with a housing including front and back walls, the front wall having a central opening therein, of a solenoid held between the front and back walls and including a plunger tube extending through said opening, and means acting to hold the back wall in operative position and to clamp the solenoid against the front wall. 50

LLOYD RITTENHOUSE.
